(57) **ABSTRACT**

A new and distinct variety of pear tree rootstock tree that
exhibits resistance to *Candidatus Phytoplasma pyri*, no
suckering, strong vigor, and is compatible with all pear
varieties.

3 Drawing Sheets

1

Botanical classification: *Pyrus x communis*.

Varietal denomination: 'ViruTherm-2'.

BACKGROUND OF THE INVENTION

The present invention comprises a new and distinct variety of pear tree that is solely used as a rootstock and known by the varietal name 'ViruTherm-2'. The new variety was discovered and selected by the breeder in a cultivated field trial environment in Bavendorf, Germany in 2014 as a naturally occurring whole plant mutation amongst a population of unpatented and unnamed pear tree plants. As such, the exact parentage is unknown. The new variety was selected and first asexually reproduced by in-vitro propagation in Cesena, Italy in 2019.

When compared to *Pyrus communis* variety named 'Kirchensaller Mostbirne' (unpatented), both varieties are stable in the ground, do not exhibit calcium chlorosis, and exhibit similar compatibility to pear varieties. However, 'ViruTherm-2' exhibits a different leaf shape, resistance to *Candidatus Phytoplasma pyri*, and excellent uniformity when compared to 'Kirchensaller Mostbirne'. Further, the resistance to *Candidatus Phytoplasma pyri* is a distinguishing characteristic of the new variety from other pear tree varieties known to the breeder.

The new variety has not been evaluated under all possible environmental conditions. The phenotype may vary with variations in environment without a change in the genotype of the plant. The new variety has been trial and field tested and has been found to retain its distinctive characteristics and remain true to type through successive asexual propagations.

2

DESCRIPTION OF THE DRAWINGS

The accompanying photographic drawings illustrate the new variety at approximately 1 year of age, with the color 5 being as nearly true as possible with color illustrations of this type.

FIG. 1 illustrates a close-up view of a plant of 'ViruTherm-2';

FIG. 2 illustrates multiple plants of 'ViruTherm-2'; and 10 FIG. 3 illustrates the roots of 'ViruTherm-2'.

DETAILED BOTANICAL DESCRIPTION

The following detailed description sets forth the characteristics of the new cultivar at approximately 1 year of age. 15 The data which defines these characteristics were collected as a result of asexual reproductions carried out in Ellerbek, Germany on field grown plants under standard growing conditions and taken under natural light. Color descriptions 20 are provided using X11 Color Names and their corresponding HEX Color Codes, accessed in August of 2022 via <http://www.farb-tabellen.de/de/farbtabelle.htm>.

ROOTSTOCK

25 Height: 150.0 cm.

Thickness: 12.0 mm.

Vigor: High.

Tree habit: Upright.

Use: Solely as a rootstock.

30 Vegetative shoots:

Overall habit.—Spreading.

Growth habit.—Straight.

Surface texture.—Smooth, with no pubescence present.

4

- Internode length.*—Average of 3.0 cm.
- Lenticels.*—Quantity: 10 per/cm. Length: 1.0 mm. Width: 0.1 mm. Shape: Oblong. Color: Khaki1, HEX #FFF68F.
- Bud.*—Length: 3.0 mm. Width: 3.0 mm. Apex shape: 5 Conical. Color: LightGreen, HEX #90EE90.
- Petiole:
- Shape.*—Straight.
  - Length.*—2.0 cm.
  - Diameter.*—0.1 cm.
  - Color.*—Khaki1, HEX #FFF68F.
- Leaves:
- Arrangement.*—Alternate, spiral.
  - Length.*—5.5 cm.
  - Width.*—4.7 cm.
  - Form.*—Elliptic-oval.
  - Apex.*—Pointed.
  - Base.*—Orbicular-obtuse.
  - Margin.*—Weakly serrate.
  - Texture (both surfaces).*—Smooth.
  - Color.*—Upper surface (young and mature leaves): DarkOliveGreen4, HEX #6E8B3D. Lower surface (young and mature leaves): LightGreen, HEX #90EE90.
- Venation.*—Type: Pinnate, alternate. Color: Light-Green, HEX #90EE90.
- Stipules:*
- Length.*—Average of 1.0 cm.
  - Margin.*—Entire.
  - Color.*—LightGreen, HEX #90EE90.
- Multiplication ability:*
- Layering.*—Very difficult.
  - Hardwood cuttings.*—Very difficult.
  - Softwood cuttings.*—Very difficult.
- ¹⁰ *Pathogen resistance:* Resistant to *Candidatus* Phytoplasma *pyri*.
- Pest resistance/susceptibility:* Not observed to date.
- Heat tolerance:* To 38° C.
- ¹⁵ *Cold tolerance:* To -25° C.
- Rootstock performance:*
- Root sprouts (suckering).*—None.
  - Anchorage.*—Stable.
  - Compatibility.*—Very good with all pear varieties.
  - Vigor.*—Strong.
- ²⁰ *Flowers/fruit:* Not observed to date.
- I claim:
1. A new and distinct variety of pear tree rootstock plant named 'ViruTherm-2', as is herein illustrated and described.
